GRAVING OR BASIN DRY DOCK

Frederic R. Harris, New York, N. Y.

Application March 6, 1943, Serial No. 478,274

19 Claims. (Cl. 61—64)

This invention relates to a dry dock and a method of building same; especially a basin or graving dry dock, which is a permanent structure on the shore adjacent the edge of a navigable body of water.

The principle of this invention is particularly applicable to the construction of decks of the so-called tremie type, in which the concrete is laid and allowed to set under water at the site of the dock. The invention has for its chief object to provide a "tremie-built" dock that is secure and durable and can safely be completed in a comparatively short time and at greatly reduced hazard and less expense.

Graving docks were formerly shorter, narrower and shallower because ships were previously smaller in length, beam and draft than they are today. But such docks were always hard to finish and deliver in a useful and serviceable condition. Water in the soil near the shore, at great pressure, and other factors, often caused heavy damage; and sometimes even brought about the collapse of the dock itself in whole or in part. Often several contractors would go into bankruptcy before one finally succeeded; and occasionally the work was actually abandoned because the completion of it was believed to be too costly or virtually impossible. Now, owing to the large size of ships, their increased length, beam, and draft and peculiar shape, much bigger docks are necessary and their construction is more difficult than ever. For example, a modern dock requires at the outset an excavation of about 1,000 feet long, 150 feet wide and 60 or 70 feet deep. Such an operation is dangerous, indeterminate beforehand in cost and uncertain of outcome. To pump the water from the entire area of the basin, then lay the bottom and erect the walls of the dock is not feasible; because the natural level of the navigable water nearby raises the hydrostatic pressure of the water in the earth on the site of the dock far too high to be counterbalanced, especially at the gate end; or permit safe and certain operation.

Different modes of proceeding still encounter problems of the most serious kind. It has been proposed to build graving docks without unwatering the site; but plans of this nature have involved the formation of large masses or bodies of concrete and other materials on the surface of the earth and their subsequent removal and lowering into the exact places in the excavation prepared to receive them. In such cases, the concrete in a plastic state was either not laid under water at all or was thus used only in a

minor degree, because there has been no practical way of controlling the concrete when spread over a large extent of ground under water so as to avoid damage; or permit reinforcing it under water in such measure as to make it serve its intended purpose and keep the volume or quantity within reasonable limits. This is particularly true of the bottom of the dock, which has to be a slab or bed of concrete many feet thick to enable the bottom to withstand hydrostatic pressure below it and the weight of the ship on top.

I have found that all obstacles can be overcome with concrete laid by tremie on the bottom of the excavation of the dock, without first unwatering the site, and my invention resides in a new way of controlling the deposit of the concrete in the wet, plastic state, so as to prevent damage or dilution; and at this stage reinforce it; with the result that, as the concrete hardens, it is bonded and otherwise joined to the reinforcing elements; increasing the strength thereof and adding to its own as well. I thus produce a bottom slab, massive and tenacious, firmly anchored to its foundation; and then the walls of the dock can easily be reared. The entire dock can be located in wet earth and complete at a great saving in time and cost, and with virtually the total elimination of the usual risks. In its final stage it will have all the dependability, stability and security that are needed by an installation of this class.

After the construction of the bottom slab, the water can be pumped out over either the entire surface, or part thereof, to facilitate the erection of the walls; or the latter can be reared without the evacuation of the water. During this step, any upward pressure beneath the bottom is successfully resisted and the foundations of the dock are in no way impaired.

The ensuing description sets forth several embodiments of my invention but this disclosure is by way of demonstration only and variations in execution may, of course, be adopted, even though not specifically mentioned herein, to the full extent covered by the broad and general meanings of the terms in which the claims appended hereto are expressed.

On the drawings:

Figure 1 is a top view showing a construction employed in the first step of building a dock according to this invention.

Figure 2 is a side view illustrating further the mode of proceeding.

Figure 3 shows a view of one part of the material employed in the dock.

Figure 4 is a top plan view showing the appearance of the finished mold forms and brace framework for the wall of the dock at its inshore or head end.

Figure 5 is a similar view showing a similar construction at the opposite end or entrance of the dock.

Figure 6 shows one of the members of said framework, for the entrance.

Figure 7 is a top view, somewhat diagrammatic, showing a modified way of building the walls of the dock.

Figure 8 is in part a section on line 8—8 in Figure 7.

Figure 9 is a view of the framing employed in this method of proceeding, seen from one side.

Figure 10 shows another modification of my invention relating to the formation of the bottom slab and walls of the dock in cross-section.

Figure 11 is a plan of the construction of the side walls.

Figure 12 is a top view presenting the same method followed in constructing the inner or head end wall of the dock.

Figure 13 shows this method utilized in the construction of the gate end.

Figure 14 shows a portion of part of the framework used with this embodiment of my invention.

Figure 15 is a cross-sectional view thereof; taken on line 15—15 in Figure 12.

Figures 16, 17 and 18 present structural details.

The same numerals of reference identify the same parts on all views.

In Figure 2, the character F indicates the excavation for the dock, on the bottom of which the concrete slab B is laid. The slab is presented in finished form at the left only, in Figure 2, but in practice it extends over the full width of the dock. The right half of Figure 2 shows in side elevation part of one of the tremie mold forms for the bottom slab, with reinforcing elements that are put into the excavation before the concrete. These forms 3 are laid side by side, but with spaces between them, as illustrated in Figures 4 and 5. When the forms and spaces are filled with concrete, the result is a continuous layer of concrete of the same thickness as the depth of the forms, from one end of the dock to the other. The excavation is made by digging or dredging, to the required depth over the selected area. Water collecting in this extensive pit, even to the point of filling the same, as shown at W, need not be removed when the concrete is poured.

To get the bottom slab down and anchor it, piles 1, made preferably of flanged steel beams of suitable length, are first driven into the sub-soil at the bottom of the excavation to a sufficient depth. These become embedded in the bottom slab B at their upper ends when the concrete sets, and are partially relied upon to resist the lifting of the dock by hydrostatic pressure in the soil when the surface water in the excavation is at last pumped out. A layer of stone or gravel 2 is also put down on the bottom, and when this layer and the piles are in position, the piles 1 project about three feet above the layer. Sometimes the dock may have to be designed wholly without reliance on the piles 1, as a precaution against the possibility that the piles might not give the anchoring effect required. In such a case the piles might even be omitted.

Due to water in the soil as above described, the upward or lifting pressure against the bottom of the dock may be enormous. The retention of the water in the excavation at full depth balances

this pressure. But with the water in the excavation the concrete must be laid under the water; and it is difficult to prevent concrete in the plastic or fluid state from being diluted and damaged

5 by the water before it sets. Docks of this general class have also been built by constructing large concrete sections, or caissons, each with bottom and high side walls, on the land adjacent the excavation; then floating them in the excavation, sinking them and connecting them together on the bottom; and finally removing the inside walls or partitions to give a single large basin; but this procedure and similar methods of making structural units of concrete on the land and then sinking them into place are very expensive and unwieldy. Laying concrete under water is, of course, easier and less expensive; but even when this can be done without damage in the construction of a basin or graving dock, the general nature of the work demands that the immense upward pressure on the extended surface of the bottom slab be transferred and concentrated, so far as possible, near the edges under the bulky and heavy side walls. Hence much reinforcement of the bottom slab is essential; but to deposit concrete under water and at the same time reinforce it, as with steel, has not heretofore been regarded as feasible. My invention successfully meets these requirements, for I have originated a method of laying concrete under water by the use of tremie or pouring equipment, and simultaneously reinforcing it; so that, as the concrete hardens, it develops full normal strength and reinforcing effect.

35 In practice, the tremie forms 3 are fully completed before laying them on the bottom of the excavation. They are lowered into the water and come to rest crosswise upon the stone or gravel 2. The forms have a width of 12 to 15 feet; and are as deep as the thickness of the slab B; and they have the shape of closed troughs or pockets, the ends and sides of which are provided by the reinforcing material to be combined with the concrete. The piles 1 project up into the forms and spaces between them. In these molds and 40 spaces between, the concrete can be poured without suffering damage before it sets; and in hardening, the concrete becomes so united to the reinforcing material that both are strengthened and stiffened in marked degree.

50 The troughs or forms 3, as illustrated separately in Figure 1, consist of steel side plates 4, with transverse or vertical corrugations, steel trusses 5 and corrugated metal end plates 6, with similar corrugations. The sides 4 may be relatively thin and flexible but are stiffened by trusses 5. Each truss includes two or more longitudinal beams 7, rigid with the sides along the outer faces thereof, and connected by vertical struts 8 and diagonal struts 9. Each truss is light but very strong, and all parts of the form are secured to one another by welding or otherwise. To the end plates 6 are fixed outside strips or battens 10. The end plates 6 are joined to the plates 4 and trusses 5 at the extremities of the latter, but project sideways beyond them. The battens serve to reinforce and stiffen the plates 6. Preferably the beams 7 are angle-shaped in cross section with vertical flanges secured to the plates 4, and turned upward.

70 Before the tremie forms are put down into the dock excavation, the frames for bracing sheet piling, when my invention contemplates the erection of such piling on the bottom slab B all around the edges thereof, and for reinforcing the dock walls reared against the inner face of such piling, are mounted on the tremie forms 3. The frames

consist of uprights 11, inclined braces 12, and struts 13. The uprights 11 project down far enough to be embedded in the concrete. These A-shaped frames are affixed by welding or otherwise in upright position to the trusses 5, at each end. Each tremie form, with four such vertical A-frames, is then transferred to the excavation; and with a chain or cable attached to each end and controlled by a crane on the surface near the excavation, lowered till it comes to rest in the right position on the gravel or stone 2. The end plates 6 project beyond the sides to such an extent that when the forms 3 are all down and the plates 6 at each end all in line, spaces 14, closed on all four sides, lie between the forms 3, and provide additional forms of slightly less width than the forms 3, as plainly appears in Figures 4 and 5. The four frames then rising from the ends of each form 3 may be entirely submerged, with their tops under the surface of the water W. But straight pieces of timber or metal 15, or other suitable members of sufficient height, may be detachably secured to the tops of the frames to project above the water and serve as markers to show the positions of the tremie forms and frames; and thus facilitate correct alignment when the forms come to rest on the gravel 2. Of course, underwater equipment and even the services of divers could be used for this purpose if necessary.

The next step is to set up the sheet piling 16 around the four sides of the area supporting the tremie forms 3 and 14, and thus erect a cofferdam on the bottom slab to enclose a space from which the water can be pumped out when the bottom slab has hardened. For the piling along the sides, horizontal wales or stringers 17 are attached to the outer sides of the aligned A-frames; being bolted, welded or otherwise secured in position. As illustrated in Figures 4 and 5, a wale 11 is affixed to each pair of A-frames at the ends of the forms 3, projecting out sideways as far as the end plates 6 and strips 10; and is lowered into the water with the remainder of the structure. All the wales are in straight alignment when the forms and frames are on the bottom of the dock excavation. A single length could also be used and attached after the forms and A-frames are in place, as by lowering it separately into the water and securing it to all the A-frames by bolts or clamps. This, however, would require the use of underwater equipment and perhaps the services of divers. Therefore, the method of first attaching wale sections in separate pieces or lengths is preferred.

This piling may be made up, for example, of members of the kind described in my Patent No. 1,937,738, covering Sheet piling, granted December 5, 1933, jointed or interlocked along their vertical longitudinal edges. They are preferably provided with hooks 18 on their faces. The wales 17 have upturned flanges with which the hooks engage. At their lower ends some of the piling members will fit into recesses 19 in the side plates 4 of the forms; and thus the whole extent of sheet piling at each side will be kept in place. For the sake of clearness only a few of such hooks are shown in Figures 4 and 5, but are, of course, employed on each piling member. The piling is put up so as to be set back a bit from the ends of the forms 3 and 14 for a purpose to be mentioned later.

Similar frames and piling are erected along the two ends of the dock. At the entrance and the

inshore ends are A-frames 20 put up along the inner sides of the end tremie forms indicated at 3', and affixed crosswise to the tops of the trusses 5 thereof. These frames support a single long wale 17a at each end of the dock, to be engaged by hooks 18 on the inner faces of the pile members and mount the latter. The lower ends of these pile members will be within the outer corrugated side walls 4 of the tremie forms 3', as appears in Figures 4, 5 and 6. The inclined braces 12' of these frames are in contact with the uppermost beam 7 of the truss 5 along the inner side of each form 3' and secured thereto by welding or otherwise. The uprights 11' also extend down into these forms. Cross struts 21 may be affixed to both sides of the tremie forms 3' at the bottom to give the frames 20 more rigidity. Any other suitable method of fabricating and mounting these frames may be adopted; and as much transverse or horizontal strut work between the plates 4 as may be needed to prevent deformation may be used with the forms 3 and 3'. The lower ends of the piling, as before, will hang down far enough to be embedded when the terminal forms 3' are filled. These lower ends may be free, or a second wale 17' may be attached to the uprights 11', below the level of the truss beams 7; and additional hooks 18 employed to engage these lower wales and support the piling 16. Each end form 3' also mounts an A-frame at each end above its inner side plate 4, and this frame supports a short wale length 17 connected to the long wale 17a. Each end form 3' with its A-frame and wales is lowered to the bottom of the excavation as a unit. The concrete is deposited by means of pipes of relatively large diameter held with their ends relatively close to the bottom of the forms in the excavation, while through these pipes the concrete is poured till the forms 3 and spaces 14 are filled to their tops. One of these pipes is shown at 22 in Figure 2, but several will be simultaneously employed to fill each form at a number of points between the end plates 6; and one or more forms may be filled together. First the tremie forms 3 and 3' are filled and then the intervening spaces 14. The center forms may be taken first, and the pipes shifted towards the forms at the ends. Any suitable means for connecting, supporting, and moving the pouring pipes 22 may be employed. As the concrete rises in the forms or troughs 3 and 3', the vertical grooves in the corrugations of the metal plates 4 and 6 are occupied by it. The subsequent filling of the spaces 14 covers the trusses 5, and the concrete embeds all of the metal parts. The various blocks or sections in the forms 3 and 3', and spaces 14, become rigidly connected to all the metal work, and immovably joined together. The final result is a continuous monolithic stratum of concrete as thick as necessary, fully reinforced crosswise, and well calculated to resist bending moments due to either pressure underneath, or the weight of a ship on top. Owing to the closeness of the joint between the concrete and the metal, because of the recessed surfaces afforded by vertical corrugations of the plates 4 and 6, a great reinforcing effect is assured. Hence, the plates and trusses can even be comparatively light in size and weight. The trusses and plates are, therefore, easy to make up, and move into position, and the tremie forms, each of which constitutes a separate reinforcing member, can be readily constructed and at relatively low cost. No large concrete bodies or

units have to be first made and then sunk into position.

As the pouring of the concrete into the forms is finished it engages the lower ends of the A-frames and piling 17 and secures them in place as it sets.

The vertical corrugations in the plates 4 and 6 greatly increase the surface of adhesion and produce a most efficient union between the concrete and the metal. Even if the concrete did not fully bond with the metal under water, the concrete after hardening assumes along the sides and ends of the forms, ridges and grooves and other recesses corresponding to the corrugations in the metal plates 4 and other recesses. When both the forms 3 and 3' and intervening spaces 14 are filled and the concrete sets, the plates 4 and 6 and the trusses 5 are tightly embedded in the bottom and the latter receives all the strength and ruggedness which could be desired.

A preferred kind of corrugations is illustrated in Figure 3. Here the side plates 4 are shown with large transverse ribs 23 alternating with grooves 24. In the tops of the ribs are small grooves 25 and at the bottoms of the grooves 24 are small transverse ribs 26. This design increases the surface of adhesion between the concrete and the metal, besides further stiffening and strengthening the latter.

When the pouring of the concrete is thus completed and hardened, earth or "back fill" is dumped against the sheet piling along the two sides and at the head end. It is heaped on the shoulders 27 of the bottom slab B, outside of the piling and assists in holding the bottom slab in place against upward pressure under it.

Figures 4 and 5 respectively show the bracing framework, the sheet piling and the tremie forms for approximately half of the dock at the inshore end and the entrance end. The dock need not be square but its ends may be rounded or trapezoidal; that is, the sides near the ends may converge somewhat to make the dock narrower therat than in the middle. In that event the tremie or mold forms near said ends will be shortened and otherwise modified in shape, as required.

When the bottom forms and A-frames have thus been put into place, the sheet piling added and the bottom slab has been poured and set, the head end wall and the side walls can be erected "in the dry" because the piling 16 makes a closed cofferdam from which the water can be pumped out. The necessary forms are then built around the inside of the sheet piling and the walls poured in place on the floor of the slab B. Part of one side wall is indicated at 28 on Figure 5, in dot-and-dash lines, and the head end wall will be the same. The side walls at the entrance will have projections 29 with shoulders 30 and a similar sill on the bottom slab for the steel pontoon gate 31.

When the dock is emptied of water, the weight and strength of the bottom slab, the weight and pressure of the earth on the shoulders 27 and against the piling 16 and the effect of the piles 1, are sufficient to resist any upward pressure on the bottom of the dock. The bottom with its embedded reinforcements has sufficient beam strength to withstand the weight of a ship; and, when not in use, to resist effectively any water pressure beneath and to offset this pressure by its own weight and the weight of the walls at the sides and ends, when the walls are added.

The A-frames, having their lower ends em-

bedded in the concrete of the bottom slab, serve as reinforcements for the side walls and inner end wall into which they are incorporated. After the side walls are completed at the entrance end, the piling 16 along this end and its frames are removed.

The side walls contain the usual chambers, passages or conduits for water, pumps, electric wires, and other purposes. Two such spaces are indicated on Figure 2 at 32 and 33. Other types of construction for the side walls are described below. The finished dock, over the floor of the bottom and entire inner surface of the walls, may receive a cement lining.

This design is very satisfactory for docks of less than maximum size and depth; and favors expeditious building and finishing. The back filling can be undertaken at an early stage of the work, thus making it possible to complete some of the crane tracks and other work structures adjacent to the excavation, prior to the erection of the side walls.

The A-shaped brace frames at the sides and inner end can be of suitable size, and so fabricated that they not only serve as reinforcing for the side walls but also help to strengthen the span of each of the floor blocks or sections of the bottom slab in the forms 3, 3' and 14. This result can be gained by inclining the braces 12 at a greater angle. They may even project somewhat from the inside faces of the concrete walls adjacent the floor of the dock. Such an arrangement increases the beam strength of these blocks after the water is pumped out from within the area enclosed by the sheet piling, and while the side walls are in course of erection.

Sometimes, further, under some conditions, the bottom pressure against the dock, after the water has been pumped out and before the side walls have been put up, may be counteracted in great part by gravel heaped on the floor of the dock in sufficient quantity to act as ballast. As the side walls are built up and their weight becomes more and more effective, the gravel ballast can be removed for use as coarse aggregate in the wall concrete. However, docks may be built by the above method without such transverse bracing or gravel ballast.

To lay down the tremie forms with the A-frames at each end in the excavation for the dock, floating derricks may be employed and, in some places, shore-supported gantries have been useful.

For larger docks, to meet more unfavorable conditions at the bottom of the excavation, the walls can be built without removing the water on the top of the slab B. In such constructions cofferdams may be built along the sides of the slab, one for each of the side and back walls. Such a method will render entirely unnecessary stone or gravel ballast and transverse bracing; for the greater portion of the water is retained in the dock and only the areas whereon the side walls are built are pumped out. But it does require a great deal of sheet piling. A more advantageous method is to proceed to erect the side walls in sections with spaces in between. A cofferdam can then be put up for each section; and after the various sections are completed, the intervening spaces can easily be filled. This method of procedure is illustrated in Figures 7, 8 and 9.

These views show how, after the bottom is laid, as above described, the wall sections are reared on areas 34, separated by spaces 35, without unwatering the partly completed dock. For this purpose,

cofferdams are put up around the periphery of each area 34. The spaces 35 are filled in later to make the walls continuous.

In this method, the places 34 for the wall sections and the spaces 35 are delineated by laying down channel beams 36 along the edges of the bottom B. They must be in contact with and set into the floor over their entire lengths, tight at the joints, and become fixed as the concrete hardens. Wherever there are corners, angle-shaped sections are used, and T-sections between the areas 34 and 35. The channel beams can be laid and finished by divers; or affixed to the tremie bottom forms in position to match and assume their proper places in the floor of the slab. The channel beams may have feet or lugs 37 which project down into the concrete.

These beams receive the lower ends of pile members joined along their vertical edges to make sheet piling 16', providing a cofferdam for a wall section as appears at the left in Figures 7 and 8. Inside the cofferdam is a bracing framework, comprising uprights 38 at the ends, uprights 39 between them, longitudinal struts 40 along the sides at top and bottom and in between; and cross struts 41 joining the struts 40. Diagonal struts 42 are put in the spaces enclosed by the struts 40 and the uprights 38 and 39 and similar struts 43 horizontally between the cross struts 41. The construction of the framework may be of iron or other suitable material with the various parts detachably bolted or otherwise secured together. The framework may have any suitable design, the details of which need not be enlarged upon here. When the framework has been put together it is lowered as a whole into the water, and the lower ends of the corner uprights come to rest at the corners of the area 35 over which a wall section is to be built. Then the piling is put into place. Suitable seats, such as are illustrated and described below in connection with Figures 14 and 15, may be provided to engage the lower ends of the uprights when the framework is let down. The uprights 38 and 39 serve as guides for some of the pile members into the recesses of the channel beams, which serve as seats for the lower ends; the remainder of the piling being easily managed. When the piling is complete it is held in line by horizontal wales 44 on all four sides, at the top and several points in the height thereof about on a level with the intermediate cross struts 41. These wales may be separate beams of any chosen shape, held together at their ends, and some of them put into place under water and bolted to the piles or to one another. If desired, they may be frames lowered down over the piling, and made in such a way that the ends of the beams can be adjusted to make them enclose the cofferdam snugly. It is believed such frames need not be more fully illustrated, as they can be of different types in practice. The cofferdams, comprising piling and wales, might also be completely finished in unitary form on land and lowered as a unit over the framework after the latter has been sunk.

When the cofferdams are in place they will appear as in Figures 7 and 8, the latter showing at the left a cross-section of the cofferdam with part of a wall in course of erection; and indicating in elevation a cofferdam enclosing the finished wall section at the right. The cofferdam is first pumped out. The concrete forms, consisting of steel sheets or plates, are then set up on the slab B, at the bottom of the cofferdam. For this purpose, the struts 40 and 41 at the bottom, their

horizontal bracing 43 and the bracing 42 below the lowermost wales 44, are removed. The concrete is then poured and lower part 29' of the wall section is thus built. When it has set, more struts are detached above it and the forms put in for the next addition. Thus the wall section rises, and the framework except for the uprights is removed part by part from the bottom up. Between the inner face of the wall section and cofferdam 10 compensating blocks 45 are inserted, to keep the piling and the wall apart. Finally, when the wall is finished the uprights and piling are removed. The bottom slab is laid as before, except that the A-frame at sides and ends are not used.

15 Whenever two adjacent wall sections are finished, the intervening places 35 are built upon. Framework may be set up thereon and piling added to cover it along its inner and outer sides only; overlapping on the adjacent ends of wall sections 34. The piling may be held at a slant along the inner faces of the side walls as these are inclined. Then the concrete forms can be put in, and the space between these sections filled in stages from bottom to top, as already described.

20 To make the piling leakproof at the bottom, grout may be laid through pipes along the outside of the piling at the bottom; thus covering also the channel seats 36.

25 When the walls are finished at the sides and the head end, the piling is removed. Backfill can then be heaped around the walls and down on the outside shoulders 27 of the bottom; and the head ends of the side walls with their shoulders 30 as shown in Figure 5 are ready for the gate. The latter is now floated into place and closed. All the water inside the dock can now be evacuated.

30 It is often advantageous to erect the walls as 40 a unit from the bottom of the excavation to the top of the dock; instead of constructing the walls on the top face of the bottom slab and thus obtaining a horizontal joint between the slab and the walls. Such a joint or seam in a large, deep dock may allow leakage of water into the dock and require special measures to prevent this. A more efficient and durable union can be produced by connecting the opposite ends of the blocks in the tremie bottom forms to the inner sides of the walls by starting the walls at the bottom of the excavation, as indicated on Figures 10 to 18 inclusive. Both the bottom and the walls are then constructed under water.

35 In these views, and particularly Figure 10, the bottom slab B is indicated as being of a width no greater than the distance between the side walls along their inner faces, except as will later appear, along the entrance end. The transverse concrete sections or blocks b of the bottom slab 45 terminate at cross plates 46 having transversely extending inclined shoulders 47. The concrete at the two ends of the bottom slab sections or blocks and in the lower portions of the side walls hardens against the plates 46. Thus, in effect, a wedging or inclined rabbeted joint is made. Under 50 ground pressure exerted upward on the bottom slab will now hold the ends of the blocks b more forcibly against these shoulders 47 and the seal there will be very tight. A similar result is obtained at the head end of the dock.

55 In following this method, tremie bottom forms are constructed with corrugated side plates stiffened by trusses 5, and end plates 6; projecting as before (see Figure 1) the same distance beyond 60 the side plates. The plates 46 are affixed to these

bottom forms between the side plates, within the end plates 6. The plates 46 make transverse partitions in the forms; and the trusses 5 extend beyond said plates. The partitions 46 are as long as the end plates 6 and project beyond the sides of the bottom forms as far as these plates 6 and battens 10. These partitions may be prepared in one piece or in parts, welded or otherwise secured to the inner and outer sides of the trusses and side plates to make in effect a single plate of the same length as the end plates 6. The bottom tremie forms are shown mostly in outline on Figures 11, 12 and 13, but are constructed essentially the same as presented in Figures 1, 2, 4 and 5, with the partitions 46 added and the A-frames omitted. Some of them, further have no corrugated plating along part of one side between the partitions 46 and end plates 6.

For the method now being set forth, each bottom tremie form also has flat horizontal plates or seats 48 on the top; for example, one at each corner and two adjacent the plate 46, to support upright beams or columns 49 which hold the tremie concrete mold forms for the wall sections. These sections are put up by pouring concrete into the wall forms without unwatering the excavation. Each wall section along most of the length of the sides will be as long as the width of three bottom tremie forms. (See Figure 11.)

The wall forms for the side walls are indicated at 50, alternating with wall forms 51. The former will cover the ends of two bottom tremie forms and one space 14 between them. The others cover the ends of one bottom tremie form and part of the width of an intervening space at each side. The wall forms 50 will have four sides. The wall forms 51 each will have two sides only extending across the bottom of the forms. This arrangement is utilized along each side wall of the dock from the head end to a point near the entrance.

With reference to Figure 11, each wall form 50 may be considered as adapted to cooperate with two bottom tremie forms, marked 3a, and the space 14 between them. Each wall form 51 stands upon a similar form 3b, which has similar spaces 14 between it and the forms on both sides. Several wall forms 50 and 51 may be needed along each side of the dock. Each row of wall forms will start with a wall form similar to that marked 51 near the entrance end and terminate with a wall form 51 at the opposite end as shown in Figures 13 and 12 respectively. The ends of the bottom forms will be designed so as to cooperate with the wall forms fully when the wall sections concrete is poured in.

In Figure 11, the two adjacent bottom forms 3a to be considered are shown at the left. Their end plates 6 are in alignment and so are their partitions 46. A wall form 50, of metal plating with vertical corrugations, assembled on land and made rigid with bracing, is lowered into place so that it will come to rest with the plating of one long side in the same vertical plane as the upper portions of the partitions 46, and the plating of its opposite long side in the plane of the end plates 6 of the two tremie bottom forms 3a. (See Figure 14.) Its plating at the ends will be in the planes of the corrugated side plates 4, of the bottom forms; but the plating of the long sides of the wall forms will project beyond the cross-plating at its ends to the same distance as the plates 6 and partitions 46 project from the sides of the two tremie forms 3a. The outside vertical beams 49 are adjacent the transverse end plating of each

wall form 50, and horizontal wales 52 are welded to the columns 49 and to the outer faces of each wall form 50. The cofferdams thus can be easily hoisted and lowered. The internal bracing of each wall form, shown diagrammatically at 50a and 50b, can be of any design sufficient to serve my purpose; and need not here be set forth in detail.

The mold forms 3a have the corrugated plates 4 along their adjacent or opposed sides, which delineate the spaces 14, terminating at the partitions or plates 46. This construction is indicated in Figure 14, which is a view of the end of the form 3a at the extreme left of Figure 11, viewed from the left. The side plate 4 in line with the cross-plating at the adjacent end of the wall form 50 (the left end in Figure 11) is illustrated as extending past the partition or plate 46 to the end plate 6; but is broken away to show no side plating between said partition and end plate on the opposite side of this form 3a. On the remaining or far side of the other form 3a there is plating 4 between the plates 6 and 46. This design is clearly indicated at the right of Figure 11, which shows the sides of the two forms 3a in line with the cross-plating at the ends of the next wall form 50 in full lines to signify that the plating 4 continues to the plane of the outside face of said wall form 50; while the remaining or adjacent sides of these two forms appear in full lines only up to the inner side of the tremie wall form above the partitions 46; to show that the plating 4 on these two sides terminates at the plates 46. The dashed lines 5 signify that only the truss work of said two sides is continued out to the extreme ends of these forms. It is to be understood, of course, that the next wall form 50 at the right of Figure 11 is of the same construction as at the left. No side plating 4 is needed in the bottom forms 3a below the wall forms 50 at points between the ends of the latter. Therefore, when the concrete is poured in the forms 3a and forms provided by spaces 14 between, it fills these forms from the shouldered plates 46 at one end to those at the other. When a wall form 50 is poured full of concrete, the latter fills the entire space at the ends of the three forms 3a and 14, under the wall form 50, from the bottom of the excavation up to the top of the wall form. The plates 46 of the forms 3a extending laterally from each of said forms half way out to bridge the intervening space 14, like the end plates 6 of the two forms 3a, are thus entirely embedded.

The wall forms 51 are of a little different type; consisting of metal plating at the two long sides only. They also have outside columns 49 connected by wales 52 to which the corrugated plating is affixed. There will be the necessary bracing between the corrugated plating along the opposite sides. The wall forms 51, as stated above, cover the end of one bottom tremie form indicated at 3b on Figure 11, and project about half way across the adjacent spaces 14. The plating 4 along both sides of this form 3b runs only out to the shouldered plates 46; and the end plates 6 and shouldered plates 46 of this form project out into the two adjacent spaces 14 to bridge half of these spaces; the end plates 6 and partition plates 46 of the adjacent forms 3a under the wall forms 50 bridging the other half. Only the trusses 5 of the forms 3b run from the plates 46 therein out to the extremities or end plates 6 of said form. The side plating of the two neighboring wall forms 50 extends out, beyond the cross-plating of their ends, about half way over the two spaces 14 at

each side of the bottom form 3b. Thus, each of the wall forms 51 will also contain the forms or concrete for a wall section long enough to cover three blocks in the bottom.

With this construction the bottom tremie forms can be filled with concrete poured through the pipes 22 (Figure 2) into them over their entire lengths between the partitions 46. To build a wall section in the wall forms, concrete is poured into the wall forms until the wall rises from the bottom of the excavation to the top of the wall form. None of the water in the excavation is pumped out till later.

To bridge the gaps between the plating on the long sides of the wall forms 50 and 51, the side plating is provided on the vertical edges with closures 53, hinged on in any suitable manner. One or more springs 54 normally tends to pull these closures shut. The springs 53 may be long helical springs, affixed at their extremities to the inner faces of the closures and the sides of the wall forms 51. Cords 55, attached to the closures, pass through eyelets 56 on the wall forms to the top, and hold the closures in the positions shown in Figure 17 when the wall forms are sunk down into position. The cords are then cut or released and the springs 54 then pull all the closures 53 shut.

Each tremie form 3a and 3b can be made up as a complete unit, as before, on the land; with all parts secured rigidly to the trusses 5; the plates 4 extending along the inner sides of the trusses from one partition 46 to the other, in the case of the forms 3b; and continued along one side only out to the end plates 6, in the case of the forms 3a. The partitions 46 are welded or otherwise fastened in place and so are the end plates 6, as before; and additional corrugated plating 4, will be extended along and be affixed to the inner face of the trusses between the end plates 6 and partitions 46 along the one proper side of each form 3a. When the wall forms 50 and 51 are sunk into the water in the excavation, the vertical plating of their longer sides will be separated in practice by gaps of about six inches. These gaps are bridged by the closure panels 53 above described. The next wall form 50 is followed by another like the wall form 51 set upon a form 3b. Suitable bracing indicated at 57, is secured between the projecting ends of the side plating of wall forms 50, and the ends of the plates 6 and 46 under them. Plates 46 are usually corrugated vertically from the shoulders 47 down to their lower edges.

Panels like those shown at 53 may also be used with the bottom tremie forms to bridge the gaps between the plates 46, and between the end plates 6 in every dock containing any of these plates. The spaces between the bottoms of the wall forms and the mold forms of the bottom slab are small and need no closures.

Reference is now made to Figures 12, 15 and 16. Each of the side walls shown in Figure 11 terminates at the head end of the dock in the section set up by means of a wall form 51 spanning a bottom form 3b, as above described. The tremie bottom form at the inner end of the dock beside this form 3b, is indicated on Figure 12 at 3'. This terminal form 3' will have corrugated plating 4 along the full length of its outer side; but along the opposite side, adjacent the form 3b, this plating will be replaced by a shouldered plate 46a extending from the line of plates 46 in one end of the other forms to the line of the same plates in the opposite ends. At its extremities, the plate or partition 46a will be bent at an

angle as shown in Figures 15 and 16. The right-angled ends of this plate 46a will line up with the same plates in the forms 3a and 3b. When the tremie wall forms are now reared over the terminal form 3' under water and concrete is poured into same, the head end wall can be built up from the bottom of the excavation to the top of the wall forms and make the same kind of joint between the end wall and the bottom of the dock as is shown in Figure 10. The plate 46a will be corrugated only below the shouldered portion 47. The terminal form 3' will comprise trusses 5 along its two sides, made up of beams 7 and such struts as may be necessary. Some of these struts are indicated in horizontal position at 58 in Figure 15. The top of the plate 46a will of course be more distant from the corrugated side plate 4 in the form 3' than the bottom portion of plate 46a, which bears the corrugations. Vertical struts or braces 59 may be extended from the top portion of the plate 46a downward and be made rigid with the trusses 7 and braces 58. All the mold forms in fact may be braced across wherever necessary. Flat plates 48 on supports 48' will be secured in place above the four corners of the form 3' and at suitable points along the two sides of this form to support the columns 49 of the wall forms. The form 3' may be braced inside in any manner required.

The wall forms for the corners shown at 60 will consist of plating forming two long sides, and cross-plating at the ends as indicated in Figure 12. The plating at one end will be extended sideways as indicated at 62; above each end plate of the form 3', like plates 6 above described, but here projecting out to one side only towards the like end plate of adjacent form 3b and similar plating 63 will project out at the same side; to line up with the side plates of the adjacent wall forms 51 for the side walls of the dock. The plating at the opposite end of this wall form 60 away from the corner of the dock will lie in the same plane as transverse corrugated plating 6' put across the extreme end form 3' under all of the wall form ends. This plating 6' will project at one side of the form as far as the side of the adjacent form 3b.

The wall forms 61 between the wall forms 60 need comprise only two long sides of sheet plating similar to the wall forms 51. Closure members 53 may be included, though not shown in Figure 12. Each wall form 61 will likewise have columns 49 to support its sides and rest upon the plates or seats 48', as in Figure 15. This construction will be continued over to the opposite side wall of the dock where a wall form 60 will be used at the corner in conjunction with the side wall forms 51 thereat. The wall forms 60 and 61, too, will be braced inside and concrete may be poured into them and the form 3' from the bottom of the excavation to the top, without removing any water. Bracing or truss-work indicated at 64 and 65 is attached to the tremie form 3' in position to extend towards the form 3b, being rigidly connected to the adjacent truss 5, plate 46a and the plating 6'. This bracing will be embedded in the block which fills the intervening space 14, thereby making the inner end of the bottom slab more rigid and immovable, obviating a tendency of the concrete to cause creeping of the form 3' away from said block when the end wall is poured. As before, the bottom slab is laid by pouring concrete first into the various forms 3a between the plates 46; and then into the spaces 14; and then

the walls are made by filling the forms at the head end and sides.

At the opposite or entrance end of the dock, the extremities of the side walls are preferably finished in the dry by enclosing two areas there with sheet piling, and pumping them clear of water. At this end, the line of wall forms along each of the sides will also terminate in a structure of the type 51, placed centrally over a bottom mold form marked 3b. Beyond this there will be two bottom forms 3c and 3c' separated by a space 14. Sheet piling 66 will be driven into the bottom of the excavation along the side of the form 3c' at the left, across the whole width of the dock. It will be continued across the ends of the two bottom forms 3c and 3c' as far as the first side wall form 51a, and from this point it will be continued across the excavation again to the opposite side.

On the outside of said wall form 51a, a rib 66a (Figure 18) will be welded to the plating and a similar rib 66b will be on the outer face of the end plate 6 on the end of the form 3b beneath. To these ribs the last member of the sheet piling 66 can be jointed as the pile members are forced down into the subsoil of the excavation. This piling will enable corrugated plates 6 to be dispensed with across the ends of the two forms 3c and 3c'; these ends being open, with only cross-trusswork or bracing; and will also render unnecessary any side plating for the bottom form 3c' along the entrance end of the floor of the dock. This form, therefore, will have along its outer side only the truss-work indicated by the dashed line 5. Along its opposite side and the adjacent side of the other form 3c, plating 4 extends up only to the shouldered cross-plates 46, in the same position as the corresponding plates of other forms. These plates project as illustrated half way out from the opposing or adjacent sides of the two forms 3c and 3c' into the intervening space 14; while at their other ends they terminate flush with the sides of the forms bearing them. The remaining side of the inner form 3c, has corrugated plating 4 along its full length, past the plates 46, out to its extreme ends. This plating 4 bridges the space between the plate 46 and end plate 6 of the adjacent form 3b, both of which are extended out across the full width of the intervening space 14.

Thus the bottom forms 3c and 3c' can be filled under water by pouring concrete into them between and up to the partitions 46, and then filling the space 14 between. Then the ends of the forms 3c and 3c' and space 14 between them are filled by pouring concrete between the plates 46 and piling 66. The adjacent form 3b and space 14 between it and the form 3c are filled likewise between and up to the cross-plates 46. With all the bottom forms in place in the excavation, from 3c' to 3', all the bottom forms and spaces 14 can be poured at the same stage in the construction of the dock. Then the side walls and end walls are put up by pouring concrete in the wall forms 50, 51, 51a, 60 and 61 as above described. Each wall form 51a at the entrance end has its inner and outer side walls extended as far as the side of the form 3c, and there connected by end or cross-plating in the vertical plane of the plating 4 of said form 3c. These wall forms 51a are filled like the others by pouring them full from the bottom of the excavation to their tops.

A line of temporary sheet piling 67 is now erected across the full width of the dock and 75

side walls, and is connected to the piling 66 near the sides of the dock by two lines of temporary piling 68. Thus cofferdams 69 are built at the entrance ends of the side walls, and a large 5 central enclosed space 70. The cofferdams 69 are then pumped out, and the offshore ends of the side walls erected to their full height in the free space thus obtained. These ends will be formed with inside shoulders 71 for the pontoon gate. When they are finished, they receive a lining on their inner faces. The floor of the bottom between said ends receives a similar lining and the space 70 between the two lines of piling 68 can be pumped out for this purpose.

15 The tops of the walls are illustrated in Figure 10 at 72. To erect them, the head end wall and side walls up to the piling 67 after the tremie wall forms are filled with the concrete, receive lines of sheet piling 73. These may be attached to the wall forms by bracing 74 and 75, and the lower ends of the pile members are embedded in the concrete. The bracing may be secured in any suitable manner. When the wall forms have been filled and the concrete has set, the dock may be pumped out to lower the water level down a little below the tops of these forms. All the work to make the tops 72 of the walls can then be done above water. Back fill is finally heaped into the sides of the excavation up to the level of the earth and the columns 49 and plating and piling on the outside faces of the walls completely interred. The finish lining 76 similarly embeds and covers the metal work on the inner faces.

35 The piling 66, 67 and 68 is as high as the finished walls. The piling 67 extends across the tops of the wall forms 51a, consisting of shorter members there and embedded in the concrete; and it can be jointed to the sides of the piling 73 and to the inner side of the wall form 51a by means such as shown in Figure 18. Between the side walls the temporary piling 67 and 68 is sealed on the floor of the dock by means of troughs put down under the water and in water-tight engagement with the floor. The lower ends of the piling are sealed in said troughs. To set the piles 67 and 68 into place, wooden frames are built and sunk down into the water to brace the piling and facilitate its erection. After the completion of the dock the piling 67 and 68, with framing and other appurtenances are removed, and so is the piling 66 across the entrance end, the remaining piling 66 being covered with earth. The piling 66 and 68 can be taken away first to enable the pontoon gate to be floated into position, the dismantling of the piling 67 then following as the final step.

60 This dock too, can be made narrower at its ends by building the walls so that they converge somewhat, and making the bottom forms of less length away from the middle of the dock.

65 By lining with plywood the inside of any of the mold forms for the walls of the dock, a surface can be obtained smooth and finished to such an extent as to make a lining unnecessary.

The tops of the walls 72 have chambers indicated at 77 therein, a roadbed 78 on top for crane tracks, and a gallery or walk 79 for workmen.

The corrugated plates attached to the framework for the sidewall forms and bottom molds must of course hold and confine the concrete and prevent escape. Even if the plates were made with openings or slits instead of corrugations for bonding of the concrete to the metal, such open-

ings would have to be small or restricted enough to prevent the passage or leakage of the concrete through them, leaving the plates substantially imperforate in use and effect.

Having described my invention, what I believe to be new and desire to secure and protect by Letters Patent of the United States is:

1. The method of constructing a basin dry dock in a water-bearing soil which consists in excavating a site, spanning the bottom thereof with transverse, metal reinforcing members having substantially imperforate recessed surfaces, pouring tremie concrete under water over said members to embed said members under water, thereby forming a continuous bottom slab consisting substantially wholly of concrete hardened under water and forming transverse blocks united to said members and to one another when the concrete sets, and rearing the walls for the dock along the sides of said site.

2. The method of constructing a basin dry dock in a water-bearing soil which consists in excavating a site, spanning the bottom thereof with transverse, metal reinforcing members having substantially imperforate recessed surfaces, pouring tremie concrete under water over said members to embed said members under water, thereby forming a continuous bottom slab consisting substantially wholly of concrete hardened under water and forming transverse blocks united to said members and to one another when the concrete sets, unwatering at least a portion of said site by means of sheet piling in cofferdam arrangement, and rearing wall construction for the dock upon said blocks.

3. The method of constructing a basin dry dock in a water-bearing soil which consists in excavating a site, spanning the bottom thereof with transverse, substantially imperforate metal reinforcing members, placing sheet piling around the excavation with the lower ends of the piling in the space between said members, pouring tremie concrete under water over said members to embed said members under water and anchor said piling thereto, thereby forming a continuous bottom slab consisting of transverse blocks united to said members and to one another and to the piling walls when the concrete sets, unwatering the space enclosed by the piling, and rearing the walls of the dock along the sides of said bottom slab.

4. The method of constructing a basin dry dock in water-bearing soil which consists in excavating a site, spanning the bottom thereof with metal reinforcing members having substantially imperforate recessed surfaces, pouring tremie concrete under water over said members to embed said members under water, thereby forming a continuous bottom slab consisting of blocks united to said members and to one another when the concrete sets, rearing cofferdams enclosing portions at the sides of the slab, unwatering said portions and rearing wall construction within said cofferdams.

5. The method of constructing a basin dry dock in a water-bearing soil which consists in excavating a site, spanning the bottom thereof with transverse, metal reinforcing members having substantially imperforate recessed surfaces, pouring tremie concrete under water over said members to embed said members under water, thereby forming a continuous bottom slab consisting substantially wholly of concrete hardened under water and forming transverse blocks united to

said members and to one another when the concrete sets, and rearing walls for the dock on the bottom of said site at the ends of said blocks.

6. The method of constructing a basin dry dock

5 in a water-bearing soil which consists in excavating a site, spanning the bottom thereof with transverse, metal reinforcing members having substantially imperforate recessed surfaces, pouring tremie concrete under water over said members to embed said members under water, thereby forming a continuous bottom slab consisting substantially wholly of concrete hardened under water and forming transverse blocks united to said members and to one another when the concrete sets, fitting sheet piling in place all around the sides of the slab to enclose the water thereon, and removing the water within the area enclosed by the piling.

7. The method of constructing a basin dry dock
20 in a water-bearing soil which consists in excavating a site, spanning the bottom thereof with metal reinforcing members having substantially imperforate recessed surfaces, pouring tremie concrete under water over said members except
25 at their ends to embed said members under water, thereby forming a continuous bottom slab consisting of blocks united to said members and to one another when the concrete sets, sinking wall forms into the excavation upon the ends of said
30 members, and filling said wall forms with tremie concrete to erect walls for the dock.

8. The method of constructing a basin dry dock in a water-bearing soil which consists in excavating a site, spanning the bottom thereof with
35 transverse, substantially imperforate metal reinforcing members, pouring tremie concrete under water over said members to embed said members in the concrete under water, thereby forming a continuous bottom slab consisting substantially wholly of concrete hardened under water and forming transverse blocks united to said members and to one another when the concrete sets, and rearing the walls for the dock upon said bottom slab.

45 9. The method of constructing a basin dry dock in a water-bearing soil which consists in excavating a site, spanning the bottom thereof with transverse, metal reinforcing members having substantially imperforate recessed surfaces, pouring tremie concrete under water over said members to embed said members under water, thereby forming a continuous bottom slab consisting of transverse blocks united to said members and to one another when the concrete sets, erecting separate cofferdams adjacent the sides of the slab, unwatering said cofferdams, rearing sections of wall therein, and filling the gaps between said sections.

60 10. The method of constructing a basin dry dock in a water-bearing soil which consists in excavating a site, spanning the bottom thereof with transverse, metal reinforcing members having substantially imperforate recessed surfaces, pouring tremie concrete under water over said members except at their ends to embed said members in the concrete under water, thereby forming a continuous bottom slab consisting of transverse blocks united to said members when
65 the concrete sets, rearing cofferdams over the ends of said reinforcements adjacent the sides of the slab, and rearing side wall construction within said cofferdams.

70 11. A basin dry dock in a water-bearing soil comprising side walls and a bottom, the latter

having reinforcing plates therein, said plates having sloping shoulders to form a wedge joint with the lower parts of the walls which is made tighter by upward pressure on the bottom.

12. A basin dry dock in a water-bearing soil having a wall and a bottom containing a concrete block abutting the lower part of the wall, said block having a reinforcing plate therein with a shoulder sloping outward and downward for wedging engagement with said wall.

13. In a basin dry dock a plurality of bottom forms having sides including reinforcing members, elevated seats at the tops of some of said forms, and wall forms having supporting columns resting upon said seats.

14. The method of building a dock which consists in digging an excavation, laying reinforcements comprising plates having sloping shoulders adjacent the sides of the bottom of the excavation and constructing a bottom slab therein with wedge-shaped sides formed by said plates, rear ing walls on the bottom of the excavation around the edges of the slab in wedging engagement with the sides of said slab.

15. The method of constructing a basin dry dock in water-bearing soil, which consists in excavating a site, spanning the bottom thereof with transverse metal reinforcing members which divide said bottom into a plurality of transverse sections, pouring tremie concrete under water over and between all said members to embed same in concrete hardened under water, thereby forming a continuous reinforced bottom slab with said members fast therein, and rear ing walls along the sides of said slab.

16. The method of constructing a basin dry dock in water-bearing soil, which consists in excavating a site, spanning the bottom thereof with

transverse metal reinforcing members, securing substantially upright plates between said members at a distance from the ends thereof, pouring tremie concrete under water over all said members except at their ends beyond said plates to embed same in concrete hardened under water, thereby forming a continuous bottom slab, and rear ing concrete walls on the bottom of the excavation at the sides of the bottom slab and simultaneously embedding the ends of said reinforcements beyond said plates in the lower parts of said walls.

17. A dry dock in a water-bearing soil, comprising a concrete bottom slab and side walls, said bottom having transverse reinforcing members therein, and vertical plates having shoulders adjacent the ends of said members, the side walls extending along said plates and resting upon said shoulders, so that pressure acting upward on said bottom is resisted by said walls.

18. The method of constructing a basin dock in waterbearing soil, which consists in excavating a site, spanning the bottom thereof with transverse metal reinforcing members including vertical plates delineating sections in said bottom, pouring tremie concrete under water over and between said members to embed same in concrete hardened under water, thereby forming a continuous reinforced bottom slab with said members fast therein, and rear ing walls along the sides of said slab.

19. The method of building a dock which consists in constructing a bottom slab with reinforcements therein, and beveling the upper corner of the slab at the side edge thereof, and rear ing a side wall on the slab overhanging said bevelled side edge.

FREDERIC R. HARRIS.
